(57) **CLAIM**

I claim the ornamental design for the tamale maker, as shown and as described.

DESCRIPTION

FIG. 1 is a perspective view of the tamale maker with a tamale wrapper;

FIG. 2 is another perspective view of the tamale maker with a tamale wrapper in a new position;

FIG. 3 is an exploded perspective view of the tamale maker;

FIG. 4 is a front view of the tamale maker;

FIG. 5 is a back view of the tamale maker;

FIG. 6 is a side view of the tamale maker;

FIG. 7 is a other side view of the tamale maker;

FIG. 8 is a top view of the tamale maker; and,

FIG. 9 is a bottom view of the tamale maker.

The broken lines in FIGS. 1 through 3 are of a tamale wrapper. The tamale wrapper is shown for illustrative purposes only and forms no part of the claimed design.

The tamale maker will hold the tamale wrappers in place while an application of the Masa spread is applied. As such, this invention allows novices to proceed with hardest part of preparing a tamale. The tamale maker also allows the user to prepare the tamale wrapper in a controlled environment to provide a faster and better product. The tamale maker accommodates various size tamale wrappers. Therefore, there is a need in the art for a tamale maker.
